Primary Examiner — Wan Laymon*Assistant Examiner* — Mark Booker(74) *Attorney, Agent, or Firm* — LeClairRyan, a Professional Corporation(57) **CLAIM**

The ornamental design for respiratory equipment, as shown and described.

DESCRIPTION

FIG. 1 is a front view of a first embodiment of respiratory equipment.

FIG. 2 is a rear view of the respiratory equipment shown in FIG. 1.

FIG. 3 is a left side view of the respiratory equipment shown in FIG. 1.

FIG. 4 is a right side view of the respiratory equipment shown in FIG. 1.

FIG. 5 is a top view of the respiratory equipment shown in FIG. 1.

FIG. 6 is a bottom view of the respiratory equipment shown in FIG. 1.

FIG. 7 is a right side perspective view of the respiratory equipment shown in FIG. 1; and,

FIG. 8 is a left side perspective view of the respiratory equipment shown in FIG. 1.

The designations of the views below as top, bottom, right side, left side, front, and rear are for ease of discussion only and are not intended to limit the respiratory equipment to one particular orientation. The respiratory equipment can be oriented in other directions which would alter these designations. The views are not necessarily shown in the same scale, and any change in scale between different views is not intended to limit the respiratory equipment to a particular size.
